UNITED STATES PATENT OFFICE

EUGENE C. FLOTO, OF AKRON, OHIO

DISPLAY AND SHIPPING CARTON

Application filed November 15, 1924. Serial No. 750,090.

This invention relates to improvements in cartons and it has special reference to a carton which may be used both for the purpose of shipping and displaying articles.

One object of the invention is to provide a carton which is constructed from a single sheet of material adapted to be folded and sealed, thereby providing an inexpensive structure possessing durability and an attractive appearance.

Another object of the invention is to provide a carton which is so constructed that one portion of the material forms an extension from a main container, this portion being provided with perforations or edges adapted to be severed to facilitate the display of articles carried by the carton.

Heretofore, so far as I am aware, cartons of the above-designated character have been constructed of more than one piece of material, or, if a single piece were used, it was not adapted to be folded to provide both display and supporting members. It has been considered necessary heretofore to provide special means to secure adjacent edges together, such as by metal fasteners or by providing slit portions in the side members and notched tabs or portions to fit into such slit portions. My invention obviates such disadvantages and provides a carton, preferably made of cardboard or similar material, which is very simple in its construction and which may be very easily assembled. It will also be noted that if it is desirable to ship the cartons alone, the construction is such as to permit a great number being packed in a very small space.

For a better understanding of my invention, reference may now be had to the accompanying drawings which form a part of this specification, and in which:

Fig. 1 is a plan view showing a prepared sheet that is adapted to be folded to form a carton in accordance with my invention;

Fig. 2 is a perspective view, partly in section, of my improved carton; and

Fig. 3 is a perspective view of the carton as it appears on display.

As illustrated particularly in Fig. 1, a formed sheet of material is shown, including a bottom member 1, which terminates in end

flaps 2, extending in opposite directions. A plurality of side members 3 also extend from the bottom member 1, each of which is provided with relatively small flaps 4. Each of the last-named flaps is cut away, as indicated at 5, which facilitates snug fitting of the parts when the carton is set up. A member 7, extending from one of the side members 3, is provided with a flap 8 and is adapted to serve as a top for the carton. It will be noted that the sheet is adapted to be bent or folded and this bending is facilitated by scoring the sheet, as indicated by the dotted lines 9, 10, 11 and 12. Adjacent the middle portions of the top member 7, a semi-circular incision 24 is made, which provides a projecting display member 25, when the top is folded along the line 13.

A supplemental portion 14 extends from the side member 3 opposite the top member, and perforations 15 serve as a dividing line for the member. The supplemental portion 14 is provided on either side with flaps 16, each of which has a substantially centrally located line of perforations, as shown at 17. The member 14 is also provided with a flap 18 extending from an intermediate portion 19. Bending the sheet of material into the desired shape is facilitated by scoring along the broken lines 20 and 21.

In forming the carton, the bottom 1 is bent along the scores indicated at 9, the sides 3 being bent upwardly and the flaps 4 inwardly. The flaps 2 are then bent along the lines 10 over the flaps 4, the meeting edges of the flaps 4 being enclosed in the fold of the flap 2 as it is bent along the line 11, as shown in section in Fig. 2. The ends of the flaps 2 are provided with angularly turned portions 22 which rest flatly upon the bottom 1 and serve to hold the flaps in position. The member 1, with its adjacent portions, as folded, is now in the form of a container 23. The top 7 is bent over along the line 12 and forms a closure for the container. The supplemental portion 14 is then bent along the perforated edge 15 over the top 7 and the flaps 16 are folded along the sides 2 and extended along the bottom, adjacent the ends of the container 23. The flap 18 engages the end portions of 100

the flaps 16 and these three members, 18, 16, 16, are sealed to the bottom of the box in any convenient manner, as, for example, by using water glass. This provides a neat and strong 5 carton in which articles of manufacture may be shipped.

To open and set up the carton on display, the perforated edges 15 and 17 are cut and the supplemental portion 14 folded beneath 10 the container, as shown in Fig. 3, to provide a support therefor. The top 7 of the container is then bent along the perforated central line 13 and folded back upon itself, and in alinement with one of the sides of the 15 container, as shown in Fig. 3, thus providing a display member which improves the appearance of the box as well as serving as a top therefor.

It will be seen that the edges, which are 20 shown as perforated, may be simply marked to indicate the line along which the edges are to be cut, and the perforations may be omitted.

Although I have illustrated but a single 25 embodiment of my invention, and have described in detail but a single application thereof, it will be apparent to those skilled in the art that minor changes may be made without departing from the spirit of the invention, and I desire that it be understood that the invention is not to be limited except as 30 may be indicated in the appended claims.

What I claim is:

1. The combination with a container, having 35 oppositely disposed pairs of sides and a bottom portion, of a display section extending from one of the sides of the container and a supplemental section extending from a different side and comprising aligned portions corresponding to the top, side and bottom portions of the container.

2. A carton comprising a rectangular container and an extension from one side of the container having flaps enclosing the ends of 45 the container and passing beneath the same, the area of the extension other than that of the flaps covering one side, top and bottom of the container being adapted to be sealed with the ends of said flaps against the bottom of the container, said extension also having 50 perforations along three edges thereof whereby it is adapted to be severed along the perforations and folded to form an inclined support for the container.

55 3. A carton comprising a rectangular container and an extension from one side of the container having flaps enclosing the ends of the container and passing beneath the same, the area of the extension other than that of the flaps covering one side, top and bottom of the container being adapted to be sealed with the ends of said flaps against said bottom, said extension also having perforations 60 along three edges thereof whereby it is adapted to be severed along the perforations and

folded to form an inclined support for the container, the top of said container having a score extending across substantially its central area being adapted to be folded along the score to provide a display member positioned in alinement with one side of the container. 70

4. A display carton comprising a body portion which serves as a container, a cover member for said body portion adapted to be bent to provide a display member, and an integral member extending from said body portion and connected thereto along a row of perforations, said last-named member being adapted to be wrapped around and sealed to the bottom of the container, whereby an inclined support may be provided for the container when the parts are severed along the perforations and folded under the bottom of the container. 75

5. A sheet of material adapted to be folded to form a display carton comprising a main rectangular section provided with two flaps extending in opposite directions therefrom having two pairs of relatively narrower oppositely disposed flaps extending from the ends of the first flaps, a flap extending from the main section between each pair of the second named flaps, and an auxiliary section supported by one of the flaps extending from the main section along a line of perforations and provided with centrally perforated flaps 80 extending from opposite sides thereof. 90

6. A display carton constructed from a single sheet of material comprising a main 100 portion adapted to be folded into a rigid container including a bottom and a plurality of sides, and a supplemental portion extending from one of the sides adapted to cover the top, the side opposite the last mentioned side 105 and the bottom of the container to which it is secured whereby the supplemental portion may be cut from the sides of the container and folded into a support therefor.

In witness whereof, I have hereunto signed 110 my name.

EUGENE C. FLOTO.
